UNITED STATES PATENT OFFICE.

JERRY ANDERSON, OF CHICAGO, ILLINOIS, ASSIGNOR TO QUALITY HARDWARE AND MACHINE CO., OF CHICAGO, ILLINOIS, A COPARTNERSHIP CONSISTING OF C. A. LAYSTROM, H. A. LAYSTROM, AND JERRY ANDERSON.

DOOR LOCK.

Application filed June 21, 1923. Serial No. 646,752.

This invention relates to a door lock of that type which normally automatically latches the door and involves a key-actuated element for locking and unlocking the same.

5 In the past it has been customary to use a square or rectangular lock casing for which it was necessary to mortise a proper aperture in the door for receiving the lock. This method required a good deal of time 10 and labor and was more or less expensive.

To overcome these objections, I have invented a lock for doors or the like which consists of an elongated casing preferably of cylindrical formation which merely requires that a suitable hole be bored in the proper edge of the door at the desired height into which the lock casing may be readily inserted.

In connection with this invention it is 20 contemplated to provide a flexible templet that may be folded over the proper edge of the door for the purpose of marking the centers for the bore, screw holes for the outer plates and whatever apertures are 25 necessary, whereby the installation of the lock is greatly simplified.

The invention comprises the novel structures and combinations hereinafter described and more particularly pointed out 30 and defined in the appended claims.

In the accompanying drawings which illustrate a preferred embodiment of this invention and in which similar reference numerals refer to similar features in the 35 different views:

Fig. 1 is a fragmentary elevational view of a door equipped with a lock embodying features of the present invention.

Fig. 2 is an enlarged longitudinal sectional view through the lock and adjacent parts of a door.

Fig. 3 is a section on the line 3—3 of Fig. 2.

Fig. 4 is an enlarged sectional view taken 45 substantially along line 4—4 of Fig. 2.

Fig. 5 is an enlarged sectional view along the line 5—5 of Fig. 2.

Fig. 6 is a sectional view along the line 6—6 of Fig. 5 with parts of the door 50 omitted.

Fig. 7 is a front elevational view of the lock.

Fig. 8 is a sectional view upon the line 8—8 of Fig. 5 with parts omitted.

Fig. 9 is a sectional view in elevation of 55 a lock embodying features of the present invention.

Fig. 10 is a sectional view taken substantially along line X—X of Figure 9.

Fig. 11 is a sectional view taken substantially along line 11—11 of Fig. 10.

In referring to the drawing, there is shown an elongated lock casing 1, which is preferably of tubular form so that the same may be inserted in a cylindrical hole bored 65 in the end of the door. A latch bolt 2 is mounted for reciprocation in the lock casing. The outer end of the latch bolt is beveled as usual and is adapted for entering a recess 3 in the door jamb. The bolt 2 is 70 provided with intermediate reduced portions 4 and 4^a, which are slotted; the ends of the slot terminating in arcuate or circular walls. The rear end 4^a of the reduced portion of the bolt is thicker than the forward portion whereby abutments or shoulders 5 are formed at the juncture of the two reduced sections on opposite sides of the slot. These shoulders 5 are beveled and converge toward the axis of the latch bolt. 75 The rear reduced section 4^a is provided with laterally projecting fins 6 which extend through diametrically opposite slots 7 in the lock casing. The extreme rear end of the latch bolt is circular and a locking 80 tongue 8 projects longitudinally from the circular portion adjacent the periphery thereof.

A cylindrical barrel 9 extends transversely of the lock casing through the slot in 90 the latch bolt. The barrel has a polygonal aperture through which the shank of the door knobs extend and an abutment or turnback 10 having converging rear faces 95 corresponding to those of the shoulders 5. Rotation of the barrel by the door knobs will cause the abutment 10 to retract the bolt, as is obvious.

The rear end of the lock casing has a pair 100 of diametrically opposite apertures as shown in Fig. 5. A cylindrical key barrel 11 extends through these apertures and has its ends crimped over the margins of the apertures. Within the key barrel are the washers 12 and 13, through which the key slot extends. The washers 12 and 13 are alternately arranged and have different internal diameters. The inner end of the key barrel is 105

closed by a slotted washer 14 through which the night latch actuator 15 extends, and adjacent the washer 14 there is a rotatable disk 16 having a central slot 17 for receiving the actuator 15 and the end of a key 18 from opposite directions. The locking disk 16 is provided with a recess 19 and the key barrel is provided with a slot 20 in the same circumferential plane as the recess. The recess 19 and slot 20 are of such a size as to admit the tongue or tail 8 of the latch bolt. When the locking disk 16 is in the position shown in Fig. 2, the latch bolt can be retracted; the tail 8 passing through the slot in the key barrel and through the recess in the locking disk. However, if the locking disk is turned by either the key or actuator 15 a half revolution to the position shown in Fig. 6, the locking disk will be in the path of the tail 8, and prevent retraction of the latch bolt. A spring 21 is confined between the key barrel and the rear end of the latch bolt for automatically projecting the bolt.

The structure shown in Figure 9 comprises a tubular casing 1 having a reciprocable sheath 22 which surrounds the latch bolt 2 and is provided with an internal rack 23 meshing with a segmental gear 24 constituting a part of the locking disk 16. In this instance the washers in the key barrel are provided with two sets of slots at right angles to each other as indicated in Figure 11, so that a quarter turn of the key will rotate the locking disk into locking engagement with the tail 8 of the latch bolt and simultaneously project the sheath 22 into the door jamb so that it will be impossible for a burglar to insert a tool between the door and the jamb and pry the latch bolt back. As shown, the sheath 22 is slotted to receive the fins 6 of the locking bolt. When the key is turned to unlock the door, the sheath 22 will be retracted as is obvious. The spring 21, in this instance, is retained against the latch bolt by a pin.

The lock casing is held in its position by a

lock plate 25, which is shrunk or affixed in a suitable way to the front end thereof and is screwed to the front edge of the door. The ornamental side plates 26 may be readily applied to the two sides of the door; the proper position having been located by the templet.

It is characteristic of this invention that the lock casing is of tubular form and requires merely the drilling of a hole in the front end of the door. The invention thus avoids the expensive mortise that usually had to be chiselled in the door. It is further characteristic of this invention that the lock is a very compact and simple structure of few parts.

I am aware that numerous details of construction may be varied through a wide range without departing from the principles of this invention, and I therefore do not propose limiting the patent granted otherwise than necessitated by the prior art.

I claim as my invention:

1. In a door lock, a tubular casing, a sheath in said casing, a latch bolt slidably fitting within said sheath and having a reduced portion defining an abutment and a slot in said reduced portion, means normally acting to extend said bolt, a turn back extending through said slot for cooperating with said abutment, a rotatable element in the rear of said bolt having a recess for receiving a portion of said bolt, said element being adapted to be rotated in the path of said bolt for locking the same and simultaneously projecting the sheath.

2. In a device of the character described, a tubular casing, a sheath in said casing, a latch bolt slidable in said sheath, means for projecting said latch bolt independent of said sheath, and key operated means for projecting said sheath, said key operated means being effective to prevent retraction of said latch bolt.

In testimony whereof I have hereunto subscribed my name.

JERRY ANDERSON.
